(57) CLAIM

The ornamental design for a swimwear hanger, as shown and described.

DESCRIPTION

FIG. 1 is a perspective view of a swimwear hanger, the opposite view being a mirror image thereof; and, FIG. 2 is a front elevation view of the swimwear hanger, the rear elevation view being a mirror image thereof. The broken lines shown in FIGS. 1 and 2 are for illustrative purposes only and form no part of the claimed design.

1 Claim, 2 Drawing Sheets

FIG. 1
